ROLPH J. LACKNER, OF OZONE PARK, NEW YORK, ASSIGNOR TO LACKNER PRODUCTS CORPORATION, OF BROOKLYN, NEW YORK, A CORPORATION OF DELAWARE

COMBINED LIGHT GLOBE AND TRAFFIC SIGNAL

Application filed April 5, 1928. Serial No. 267,620.

This invention relates to a combined street light and traffic signal, and one object of the invention is to provide a globe which may be applied to an overhead street light and 5 serve to permit a street to be well illuminated as well as constituting a traffic signal.

Another object of the invention is to so 10 form the globe that lenses constituting traffic indicators may be of sufficient size to be readily seen and at the same time so disposed upon the globe that they will not prevent a street from being well illuminated.

Another object of the invention is to so 15 form the globe that when it is applied to a light a bulb about which the globe is disposed will be located above the centers of the lenses and thereby cause rays passing from the bulb through the lenses to be directed downwardly at an incline and thereby 20 prevented from shining directly in the eyes of a person driving an automobile along a street.

Another object of the invention is to provide the globe with side extensions against 25 which lenses formed separate from the globe may be secured by cement and firmly held in place without danger of the globe or lenses being broken by expansion and contraction during heating and cooling of the globe and 30 lenses when in use.

The invention is illustrated in the accompanying drawings, wherein

Figure 1 is a view showing the improved 35 street light and traffic signal in side elevation;

Fig. 2 is a top plan view of the same;

Fig. 3 is an enlarged sectional view through the improved globe, and

Fig. 4 is a sectional view through a globe 40 illustrating the manner of forming the globe and applying the lenses to the same.

The post or standard 1 may be of any height desired and is to be erected in a vertical position either in the center of a street 45 crossing or upon a sidewalk sufficiently close to the curb to permit the combined lights and signals carried thereby to be easily seen by a person driving an automobile along a street. Arms 2 extend from adjacent the upper end 50 of the post and are provided with depending

end portions 3 carrying lamps 4 which are preferably electric lamps of a conventional construction. Each lamp is provided with the usual socket to carry a bulb 5 and includes a hood 6 to which a globe is to be 55 connected, and it will be understood that when a globe is connected with the hood it will enclose the bulb. The globes are indicated in general by the numeral 7 and each carries lenses 8 which project from its sides 60 and are so spaced from each other about the globe that pairs of lenses are disposed in opposed relation to each other, as shown in Fig. 2. If the light and signal is erected at a street intersection, one set of opposed lenses 65 of each globe will be preferably green and the other set red but the red and green lenses of one globe will be at right angles to the corresponding lenses of the other globe. Therefore, when one lamp is illuminated, it 70 will indicate that traffic is to proceed in one direction across the street intersection and when the light of the other globe is illuminated, it will indicate that the reverse movement of traffic is to take place. The arms 2 75 extend diagonally, as shown in Fig. 2, so that both globes can be readily seen from either direction.

The globes are of a duplicate construction and each consists of a hollow globular body 9 80 which is formed of glass of a translucent nature so that light may pass through it but at the same time the globe serves to prevent the bulb from being directly seen and the driver of an automobile blinded by a bright 85 light. This globe is substantially spherical in its outline, as clearly shown in Figs. 1 and 2, and is formed with an upstanding open neck 10 adapted to be fitted into the hood 6 and secured therein in a conventional manner. The upper portion of the globe about the neck is unbroken and the lower portion also constitutes a segment of a sphere and is preferably formed with a depending nipple 90 11. Between its upper and lower portions the globe is formed with side extensions 12 formed in opposed relation to each other and when the globe is originally molded each of the side extensions is provided with a portion 95 13 of a reduced diameter leading from an

annular shoulder or flange 14 and closed at its outer end by a head 15 which extends inwardly, as shown in Fig. 4. If the globe is to be used in connection with a light serving merely to illuminate a street, it is employed in the condition in which it is removed from its mold or, in other words, each side extension remains in the form shown at the left of Fig. 4, but if the globe is to serve as a traffic signal, one or more lenses will be applied, as shown in Figs. 1, 2 and 3. If the signal is employed at a street intersection, lenses will be applied to all of the side extensions and they may be of different colors, such as red and green, or any other color desired, such as yellow, to indicate a dangerous crossing. If the signal is erected at the end of a street or where a street is interrupted by a park, only one lens is needed and this will 20 preferably be red to indicate danger or the end of a street.

When a lens is to be applied to a globe, the reduced portion of the side extension to which it is to be applied is removed substantially even with the bordering shoulder or flange 14 and the outer surface of the shoulder and any remaining portions of the reduced extension are ground so that an uninterrupted outer surface will be provided. This surface 30 will be roughened during the grinding process so that when cement is applied to it it will firmly adhere to the flange. The lens is slightly smaller in diameter than the external diameter of the flange and when cement is applied to the marginal portions of the lens or outer surface of the flange and the lens set in place the cement when dry will serve to very securely retain the lens in engagement with the globe. The globes are initially molded with the extensions so that when 40 they are to be used the lenses may be applied or not according to the particular use to which the globe is to be put. From an inspection of Fig. 3, it will be readily seen that 45 when the globe is in place the bulb 5 terminates above the centers of the lenses and, therefore, light rays emitted by the bulb will pass outwardly through the lenses at a downward incline, and in the preferred arrangement will strike the pavement about a hundred feet from the post. Therefore, the light 50 passing through the lenses will not glare in the eyes of a person driving an automobile along a street.

Having thus described the invention, I claim:

1. In a combined street light and signal, a globe of light penetrable material adapted to be connected with a light carrier in 60 closing relation to a light carried thereby and having its intermediate portion formed with a hollow side extension projecting outwardly therefrom and formed with a circumferentially extending shoulder, an opening being formed in the outer end of the exten-

sion bordered by the shoulder, and a tinted lens secured against said shoulder in covering relation to the outer end of said extension and constituting an indicator.

2. In a combined street light and signal, 70 a globe of light penetrable material consisting of a hollow globular body having its intermediate portion formed with hollow outwardly extending side extensions normally closed at their outer ends, flat annular shoulders being provided about the side extensions adjacent their inner ends, one extension being cut off at its shoulder to provide an opening bordered by a flange, and a lens secured against the flange in covering relation to the opening and constituting an indicator.

3. A method of forming a combined signal 80 and street light globe consisting of molding a hollow globular body of light penetrable material, the body being formed with a hollow side extension closed at its outer end and reduced in diameter from its outer end to adjacent its inner end to form an outstanding annular shoulder, cutting off the side extension flush with the shoulder to provide the body with a side opening bordered by an inwardly extending flange having a roughened face, and disposing a lens in covering relation to the side opening with its marginal portions secured against the outer surface of 90 the flange.

4. A method of forming a combined light globe and signal consisting in molding of light penetrable material, a hollow body having a hollow extension at its side, cutting off the extension to form an opening through the body, disposing a lens in covering relation to the opening, and securing marginal portions of the lens to the body about the opening.

In testimony whereof I affix my signature.
ROLPH J. LACKNER. [L. s.]
